CASING HEAD FOR PRESSURE DRILLING

Frederic W. Hild, Los Angeles, Calif.

Application November 2, 1936, Serial No. 108,777

11 Claims. (Cl. 255—1)

My invention relates to equipment for placing and supporting the several casings in gas and oil wells, and pertains more particularly to the supporting heads for the casings and to a novel method of landing and securing the casings and the heads in place during fluid pressure conditions.

Various forms and arrangements of casing heads for well casings have been proposed and used, but all of them require absence of fluid pressure at the heads when landing or securing them in position. Therefore the hole is usually filled with mud fluid of sufficient density to "kill" the well and prevent flow from pressure formations during the period of landing and securing the casings. Obviously all of these forms require removal of the well control column comprising the master valve and the blowout preventer in order to secure and seal the upper end 20 of the casing to the casing head.

But reliance upon mud fluid alone to hold the well pressure often has proved inadequate and dangerous and has resulted in some costly blow-outs. It is an object of my invention to provide 25 a casing head having means for sealing against the casing or the casing terminal collar before removal of the well control column. Another object is to seal the casing with respect to the casing head before securing them to each other.

The present invention provides a method and suitable equipment for placing casings and securing them together in a live well or during pressure flow of fluid therefrom. The economic importance and value of this to the petroleum industry may be seen upon consideration of the following: Experience has shown that most oil fields have several producing strata. But on account of the limitations of the casing head equipments, the present well practice has been based 30 on producing from only one of the several strata. Sometimes this formation may be abandoned for a lower sand; this requires drilling deeper. Occasionally a known upper producing sand may be utilized by plugging back which involves cutting and rearranging the casings in the well; but owing to the discouraging uncertainties involved in this, such undertakings are quite exceptional. In addition to the difficulty and uncertainty of 35 making a good pack off in the right place, there is the probability of little or no production due to mud intrusion during the drilling period and thereafter, and also to the migratory character of underground fluids.

My invention herein described makes available to the producer each productive formation as it

is encountered and also enables him to utilize in a single well any or all of the several producing sands, at the same time. Thus on drilling a well to the first upper sand, the producer may set a casing and flow the production through the inter-casing space, and while it is flowing he may drill on down to the next pay sand, and bring this in similarly, and so on downward to the other productive horizons.

Manifestly by means of the present invention 10 the cost of drilling for oil and gas will be greatly reduced. Also the output per well in a field of multiple sands will be vastly increased. Moreover it will not be necessary to defer for an indefinite later time the endeavor to obtain fluid 15 from another sand, which may then prove abortive.

The invention provides other advantages. It is well understood that a minor portion of the weight of a string of casing may be borne by its 20 lower end and that the major portion should be suspended from the terminal collar at the upper end. The lower end of the casing string is therefore in compression and the upper part is in tension. It is important to suitably apportion these 25 loadings, and to hold the casing straight in the hole. For supporting the upper part of the casing each casing head of the usual type contains a terminal collar which either is threaded onto the casing at the top, or else is a set of serrated 30 slips which grip the casing. In both types, the seated position of the terminal collar in the casing head is definitely fixed with no possible variation therefrom vertically. Moreover seal cannot be effected until after the terminal collar is 35 finally seated.

The two types of terminal collars have certain advantages and disadvantages when compared with each other. Thus the threaded collar which may also be welded to the casing, is better adapted 40 for sealing against the fluid and requires fewer additional parts of its casing head assembly. But it necessitates quite accurate knowledge of the location of the bottom end of the casing and also that the final upper joint of casing be cut 45 and threaded to exact length.

The tapered slip type of terminal collar enables lifting or stretching the casing to the desired tension as it is landed in the slips, after which the casing is cut off flush at the top of 50 the casing head. Thus it is less dependent upon accurate knowledge of casing point or upon the exact length of the final joint. On the other hand the teeth of the slips must cut the equivalent of threads into the casing which accordingly

is subjected to combined crushing and tensile stresses continuously. Moreover movement or change of position due to well disturbances is more likely with this type than with the threaded type.

It is an object of my invention to provide a casing head having a terminal collar which may be threaded or welded to the final joint of casing and which provides a substantial range of vertical position for the terminal collar, so that the casing may be stretched through said range to the desired tension.

For forcing pipe into a well against pressure, suitable snubbing equipment is essential. The present invention includes a unique yet very simple hydraulic snubbing jack capable of snubbing into or out of the well some 45 to 80 feet of drill pipe without stopping, and with only one grasping of the drill pipe.

Other objects and advantages of my invention will be apparent from the following description and the accompanying drawings:

Figure 1 shows the equipment embodying the invention installed in a derrick.

Figure 2 shows in part section the casing head assembly for several concentric casings.

Figure 3 is a view in horizontal section taken on the line 3—3 of Figure 2.

Figure 4 shows a slip head and slips in a rotary drilling machine for holding drill pipe against vertical movement.

Figure 5 shows the snubbing jack locked to the slip head of Figure 4.

Figure 6 is a horizontal section taken on the line 6—6 of Figure 5.

Figure 7 is a longitudinal section on line 7—7 of Figure 5.

Figure 8 shows in part section the equipment and the first stage of the method for landing casing against well pressure.

Figure 9 shows in part section the equipment including the landing tool in the later stage of the method for landing casing against pressure.

Figure 10 shows the final stage of the method illustrated in Figures 8 and 9 and shows the casing secured in its casing head.

Figure 11 is a fragmentary view showing an alternative arrangement of a portion of the casing head assembly of Figure 2.

Referring to the drawings, the casings 14 and 15 are suspended from casing head 17 while casing 16 is suspended from casing head 18. Superimposed upon these in fluid tight connection are the roller valves 19 and 20, the nipple 21, flow cross 22, nipple 23 and control head 24 respectively. Above these on the derrick floor beams is the rotary machine 25 which contains the stripper bushing 26, the latter extending into the control head 24. The last named contains the hollow resilient packer 24a together with a wear packer 24b which bears in sealing contact against the lower part of the stripper bushing 26. The rotary machine and the control head are connected by the expansion joint 27. All of the apparatus listed in this paragraph with the exception of casing heads 17 and 18 are shown and described in my co-pending application Nos. 86,140 and 91,554 filed June 19 and July 20, 1936, respectively.

Secured to the stripper bushing 26 is sliphead 28, and breech locked to the latter is the lower end of snubbing jack 29. The upper end of the snubbing jack is linked onto the hook of traveling block 30 which is suspended from the crown block (not shown) of derrick 31 by means of a

ble 32. Extending upwardly into snubbing jack, and downwardly through the sliphead, the stripper bushing, the casings, the casing heads and the intervening apparatus is the drill pipe 33 having tool joints or collars 34.

Referring more particularly to Figures 2, 3 and 11, the outermost casing 14 is suitably secured as by welding to the casing head 17 which rests upon a suitable foundation, and is the landing and anchorage base of the apparatus and the members superimposed upon it. A pair of vent pipes 35 are threaded into the sides of the casing head for conducting fluid laterally away from casing 14. The upper end of the casing head is flanged radially outward as at 36. The upper face of the flange is grooved as at 37 to receive a temporary gasket for packing against a control device during drilling such as roller valve 19.

The casing head has a large central bore 38 co-axial with and the same diameter as the inner diameter of casing 14. A groove in the bore 38 contains the hollow resilient expandible packer 39 which may be similar to packer 24a in control head 24, illustrated and described in my co-pending application No. 91,554. The packer 39 when expanded by a suitable pump 39a constitutes an effective, controllable seal against the terminal collar 40 of the next casing 15 for preventing escape of well fluid from outer casing 14. The bore 38 is counterbored at the flange 36 to receive a gasket 41 preferably metallic which is a second seal against terminal collar 40 for the same purpose. The outer surface of the terminal collar is cylindrical and fits metal to metal in the bore 39 of casing head 17.

A gland 42 bears against the metallic gasket 41. The outer cylindrical surface of the terminal collar is recess grooved at 43 to receive the split holding ring 44 which may bear on the gland 42 through shims 45 which may be interposed between the gland and the holding ring, or through the adjusting screw 45a which is threaded through the holding ring. The terminal collar is inner threaded at both ends, the lower end receiving the casing 15 and the upper end receiving the casing head 18. The bolts 46 tie the holding ring 44 to casing head 17 at flange 38, and prevent radial displacement of the ring. Spacers 46a surrounding the bolts 46 may be interposed between the holding ring and the flange thereby transmitting to the casing head the weight carried by the ring. The adjusting screw 45a bearing on the gland 41 may vary and adjust the packing effect of gasket 41.

The collar 40 at the upper end of its upper thread has counterbore 47 which forms a seat for casing head 18. During the drilling stage prior to setting casing head 18, the collar 40 may receive in seat 47 an adapter similar to adapter 48 to which may be secured a master gate or blow-out preventer exemplified herein by the roller valve.

The casing head 18 at its lower end 49 is threaded and shouldered to fit snugly into the thread and seat 47 of terminal collar 40 thereby effecting metal to metal seal against the escape of well fluid from casing 15. A gasket 50 between the seat 47 and the shoulder of casing head 18 provides additional effective seal for the same purpose. The casing head 18 in other respects is similar to casing head 17. Thus casing head 18 has the lateral vent pipes 51, the upper flange 52, the hollow packer 53, the metallic gasket 54, the gland 55, the split holding ring 56 and shims 75

57. Likewise the terminal collar 58 is similar to terminal collar 40. The inner casing 16 is threaded into terminal collar 58 which fits snugly into the central bore of casing head 18, the collar being engaged and held by holding ring 56.

5 The adapter 48 has the threaded and shouldered lower portion which with suitable gasket fits snugly into the terminal collar 58. The upper portion of the adapter is flanged radially outward and to it may be secured a control device such as roller valve 59.

10 For setting or cementing casing either in the absence of well pressure or against it, the collar may receive in its upper thread a length of pipe 15 serving as a landing and cementing tool. It is obvious that the arrangement allows considerable range of vertical movement of the terminal collar, the shims 45 and/or the adjusting screw 45a enabling a substantial range.

20 The stripper bushing 26 in the rotary machine 25 contains the resilient packer 60 through which extends in fluid tight seal the drill pipe 33. The upper part of the bushing 26 forms the radial flange 61 and the taper bored slip bowl 62, the 25 last named being adapted to receive the usual downslips for gripping and holding the drill pipe against downward movement.

25 Referring particularly to Figures 4, 5, 6 and 7, the sliphead 28 has a body 63 the lower portion 30 of which forms the neck 64, which is bored to fit snugly on the outer cylindrical surface of bowl 62 of the stripper bushing 26. The flanged base 65 of the body 63 radiates outwardly from the lower end of neck 64 and rests upon flange 61 of the 35 stripper bushing, being held firmly thereto by the hold down brackets 66 of the rotary machine 25. A gasket 67 between the flanges aids in making fluid tight the connection of the sliphead 28 to the stripper bushing 26. The upper portion 40 of body 63 forms the female half of breech lock 68 and also the tapered head 69 the latter having a gasket 70 on its external tapered surface.

45 Within the body 63 are the downslips 71 and the upslips 72 for gripping the drill pipe. Downslips 71 co-operate with the tapered bowl 62 of the stripper bushing 26. Upslips 72 co-operate with the tapered head 69 the inner surface of which is taper bored to conform with the slips. For moving the slips into and out of gripping 50 position, duplicate and independent shifting means are provided. Thus slip ring 73 surrounding the downslips 71 has inwardly projecting lugs 74 which engage the downslips 71. The slip ring has trunnions 75 which are engaged by the ends of a shifter yoke 76. The yoke is pivoted by means of shaft 77 in bearings 78 and 79 in the side of body 63. One end of the shaft projects outside the body at bearing 79 and is flat faced to receive a wrench or lever. 55 A closure plug in bearing 78 and a stuffing box 80 in bearing 79 prevent escape of fluid but permit rotative movement of the shaft 77. Rotation of the shaft and the yoke imparts vertical movement to the slip ring thereby moving the downslips 71 into or out of the tapered bowl 62 of the stripper bushing. Likewise by means of shaft 81 with similar yoke and slip ring arrangement, the upslips 72 may be moved vertically 60 into or out of the tapered head 69 of sliphead 28.

65 Sometimes slipheads must be rotated and as all slipheads are subject to vertical thrust in both directions, provision for thrust bearings must be made for such rotative service. Sliphead 28 transmits the thrust to the rotary ma-

chine 25 which has the usual thrust bearings common to all such machines. This unique combination simplifies the construction so that the same sliphead 28 may be used advantageously without the rotary for non-rotative operations, such as casings or tubings which must be snubbed, see Figure 8.

70 Considering now the snubbing jack 29, the body of this is the long tubular cylinder 82 on the lower end of which is threaded the base 83. The lower portion of the base is taper bored 10 to fit on the taper head 69 of sliphead 28; the bottom of the base forms the male half of the breech lock 68. Thus by setting the snubbing jack on the slip head and giving the jack a quarter turn, both are connected tightly together, 15 the gasket helping to effect fluid tight seal. Within the base 83 is formed the interceptor 84 as part thereof.

20 The tubular cylinder 82 contains the piston 85 from which are suspended the grab hooks 86. The piston 85 has the body 87 on which is suitable packing 88 which bears against the inner wall of tubular cylinder 82. Within the piston body are two opposing valves 89 and 90, urged 25 to their seats by a light spring 91. Fluid pressure on the upper side of piston 85 tends to open valve 89 and to force valve 90 into its seat. Conversely fluid pressure below the piston acts to open valve 90 and to close valve 89.

30 The lower portion of piston body 87 forms the shank 92 in which the pin 93 at right angles to the piston axis serves as trunnion for suspending the grab hooks 86. Also suspended on pin 93 in a central slot of shank 92, is the valve 35 stem 94 for the valve 90. The valve stem has an elongated slot through which the pin passes such that upward vertical movement of the stem with respect to the piston body 87 will lift valve 90 from the seat and thus open it.

40 The grab hooks 86 are bored to two diameters thereby forming the shoulder 95 near the lower end, such that the grab hooks may surround the collar or tool joint 34 of the drill pipe 33, the shoulders 95 being adapted to intercept 45 the under shoulder of the tool joint for holding or suspending the drill pipe. The inner lower ends of the grab hooks are flared outwardly. The outer diameter of the lower ends is only slightly less than the inner diameter of tubular cylinder 82, so that when the grab hooks are 50 closed around the tool joint, the hooks cannot open within the tubular cylinder and cannot release the drill pipe. When the piston 85 approaches its lowest position in the cylinder 82 the lower ends of the grab hooks meet the interceptor 84 in the base 83. The interceptor is so shaped and positioned in the base 83 that the flared inner ends of the grab hooks are the first to meet the interceptor, so that continued downward movement of the piston forces 55 the grab hooks apart away from the drill pipe and tool joint, thereby releasing the drill pipe.

60 The upper end of the tubular cylinder is closed by the cap 96 which has the bale 97 for linking onto the traveling block 30. A pipe 98 65 having the valves 99 and 100 connect the base 83 of the snubbing jack to the cap 96. A flexible hose 101 connecting to pipe 98 between the valves leads to a pipe 102 which has a valve 103 and leads to a suitable source of fluid pressure 70 supply such as the boiler feed pump. A pipe 104 having valve 105 connects pipe 102 to the well pressure. A valve 106 controls a drain from the base 83. Gages 107 and 108 indicate fluid pressure on either side of piston 85.

When the snubbing jack 29 is not in use, it stands in a corner of the derrick, the piston 85 being at its lowest position. The valve stem 94 therefore has been pushed upward and the valve 5 90 is lifted from its seat. The weight of the liquid in the tubular cylinder 82 is ample to overcome the light spring 91 so that both valves being open the liquid drains out of the snubbing jack.

10 During pressure drilling, the well pressure tends to urge the drill pipe upwardly. For several hundred feet below the surface depending upon the well pressure, it is necessary to hold the drill pipe against upward movement. Below 15 this depth the weight of the drill pipe with collar and bit is enough to overcome the well pressure and the pipe moves downwardly by its own weight. For example: with 250# well pressure at or near the surface, the drill pipe must be 20 held against upward movement until some 400 feet of pipe is in the hole; below that the pipe will move downwardly unless restrained at the surface. Similarly for 1000# well pressure it is necessary to hold or snub for some 1400 to 1500 25 feet depth. It is well understood that the upper part of the hole is drilled most rapidly and that the time required per foot of hole increases with depth. It is therefore apparent that upslips and the snubbing jack are needed for the 30 less portion of the total drilling work and time, and that the stripper bushing 26 with ordinary downslips will suffice for much the greater part of the time.

Figure 4 shows the roller valve 19 closed as 35 master gate thereby shutting off the well fluid. The bit, the drill collar or drill pipe and the stripper bushing 26 may then be inserted into and through the rotary machine 25 and the control head 24, whereupon seal is effected on the 40 drill pipe and the stripper bushing. As the bit rests upon the closed rollers of valve 19, the ordinary slips need not be applied in the taper bowl 62 of the stripper bushing except it be to prevent rotative movement while adding drill pipe so that a "double" (two lengths) projects 45 above the stripper bushing. On very high derricks this may be a "thribble" or even a "fourble". The ordinary slips if they were used are then removed and the sliphead 28 is put in place. The well pressure gage will indicate whether to 50 apply downslips 71 or upslips 72 before opening roller valve 19. If sufficient well pressure is indicated the slips need not be applied, but the snubbing jack 29 is then picked up by the traveling block 30 and hoisted until it is above the 55 tool joint at the top of the drill pipe. Upon lowering the snubbing jack the valve stem 94 enters the tool joint and drill pipe, and the grab hooks 86 being wide open, the piston 85 approaches the tool joint until the shank 92 meets 60 the tool joint. Then as the snubbing jack continues its descent, the grab hooks close around the tool joint and when the snubbing jack is resting on and locked to the sliphead 28, the 65 piston 85 is at the top of tubular cylinder 82. The space between the piston and the packer 60 of the stripper bushing 26 now forms a fluid tight chamber.

As a precaution against sudden lessening or 70 loss of well pressure such as may occur when well flow is by "heads", liquid may be admitted below the piston 85 through valve 99, so as to partially fill the cylinder because the air trapped therein will provide a resilient cushion for the 75 piston, should the drill pipe move downward by

its own weight. Of course the gage 107 will indicate this condition. Obviously if external pressure be applied to the fluid under the piston the latter with its suspended drill pipe load may be moved upwardly.

However with adequate well pressure and upon opening the roller valve 19, the bit and drill pipe will tend to move upwardly. Then by admitting liquid from a pressure source through valve 100 to the upper side of piston 85, the 5 drill pipe will be forced downward against the well pressure and then the upslips 72 in sliphead 28 may be applied. The snubbing jack is then given a quarter turn thereby freeing it from the sliphead; the traveling block will place 10 the jack in its corner in the derrick, the valve 90 will open automatically and the liquid in cylinder 82 will drain therefrom as previously described. The operation for snubbing out of the 15 well is quite similar, the fluid and the pressure 20 on the upper side of piston 85 together with the control valves regulate the upward movement of the drill pipe.

Referring to Figures 8, 9, and 10 which illustrate the method of landing casing against well pressure, the block 109 is substituted for the 25 rotary machine 25. The stripper bushing 110 is adapted to receive casing 15 and is threaded into the control head 24 in substitution for the wear 30 packer 24b. The hollow packer 24a is then expanded against stripper bushing 110 thereby effecting seal against escape of well fluid. The 35 sliphead 111 differs only in size from the similar sliphead 28. The other control equipment including the casing head 17 are the same as for 40 the drilling cycle previously described.

The casing 15 is shown to have at its lower 45 end a conventional valved float shoe 112 for cementing service. The elevator 113 of Figure 8 is replaced by a snubbing jack of larger size but 50 otherwise the same as snubbing jack 29. The casing is then forced into the well in the same manner as previously described for drill pipe 33. When the casing moves down of its own weight, the snubbing jack is set aside and the elevator 55 113 is used for the remaining depth. The sliphead is removed and the ordinary slips are used in the taper bowl of the stripper bushing.

Just before adding the terminal collar 40 to the last length of the casing 15, the string is 60 held fluid tight in the roller valve 19, the last ordinary collar supporting the string on the rollers. The stripper bushing 110 is then removed and the conventional slip spider 114 is substituted. The terminal collar is now added to the 65 casing, and into the upper end of the collar is threaded a landing and cementing tool 115, which may be a length of casing.

The next step may be one of several alternatives. Thus it is possible to "lubricate" the 70 terminal collar 40 into the casing head 17 by means of roller valves 19 and 20 if the latter are provided with rollers for engaging the casing.

The simple and preferred way is to expand 75 the packer 39 of the casing head against the casing 15, thereby effecting seal and then lowering the string until the terminal collar is in the casing head preferably somewhat below its final position. Also, optionally, the packer 24a in control head 24 may be expanded for effecting additional seal on the casing string.

The casing 15 may now be cemented in the usual manner, the cement being forced through the landing tool 115 which thus serves as a cementing head. After the cement has set, the 75

casing may be lifted or stretched to give the desired tension, and the slip spider raised and supported on blocks. Then by disconnecting roller valve 19 from the casing head, the control column, comprising the two roller valves, the control head 24 and the intervening devices, may be lifted as a unit and likewise supported on temporary blocks. Now the metallic gasket 41, the gland 42, the shims 45 (if needed or preferred) and the holding ring 44 are put in place, and the landing tool 115 is removed.

A suitable adapter like adapter 48 is inserted and screwed into the upper thread of the terminal collar 40. The roller valves and the control devices above them are lowered and bolted to the adapter. Meanwhile, rollers suitable for the next drilling cycle and casing string 16 have been placed in the valves 19 and 20.

If after the outer casing 14 had been landed and cemented, the drill had found a productive sand below the casing, the fluid from this formation would have been available at the flow cross 22 and also at the vent pipes 35. With the system herein described, drilling could continue, circulating as much of the fluid as might be needed for bringing out the drill cuttings, until setting casing 15. Then the flow will be up between the casings 14 and 15 and out through the vent pipes 35, the flow cross 22 then receives the fluid which may flow or be circulated through the casing 15. In like manner production from a second formation and a third formation and so on may be brought in the one well.

Although I have described several specific embodiments of my invention, it will be obvious to those skilled in the art, that various modifications may be made in the details of construction, the general arrangement, the association of the several co-operating parts and the application of my invention without departing from the spirit thereof or the principles herein set forth.

What is claimed is:

1. In a snubbing jack for engaging a drill string or casing in a well, an elongated fluid pressure cylinder closed at one end and having an open end for detachable connection to the top of a well column, a piston therein, means for passing fluid under pressure to either side of the piston, and valve means for automatically draining the cylinder and operated, after removal of the cylinder from the well column, upon standing the cylinder on its bottom.

2. In a snubbing jack for controlling the lowering or raising of pipe in a well, a cylinder adapted to be attached to the top of a well column, a piston therein, means controlling the fluid pressure on either side of the piston, and means carried by the piston for engaging a string of pipe, comprising pivoted grab hooks, and means carried by the cylinder for releasing the hooks when the piston is lowered to a predetermined extent in the cylinder.

3. A hydraulic jack for controlling the insertion or withdrawal of a pipe in a well having confined fluid pressure, comprising: a cylinder adapted to surround the pipe substantially coaxially and to be attached fluid tight to the top of the well column, pipe engaging means and a piston in the cylinder, said means being adapted to hold the pipe to the piston for forcing the pipe to move in either direction in accordance with the movement of the piston, and means for passing fluid under pressure into the cylinder for moving the piston and pipe engaging means in either direction.

4. A snubbing jack for controlling the lowering or raising of a string of pipe in a well having confined fluid pressure, comprising: a cylinder adapted to surround the pipe substantially coaxially and to be supported in substantially coaxial relation to the well, a piston in the cylinder, and grab hooks carried by the piston for loosely and at least partly embracing the pipe and engaging an outwardly projecting member of said string for checking said movement.

5. In well equipment, a snubbing jack for controlling the lowering or raising of pipe in a well, comprising a cylinder and a piston, means for passing fluid under pressure above or below the piston, said piston having a relief aperture therethrough, and oppositely closing valves in the aperture.

6. In well derrick equipment, a snubbing jack for controlling the lowering or raising of pipe in a well, comprising: a cylinder and a piston, means for passing fluid under pressure above or below the piston, and means carried by the piston for draining the fluid from above the piston.

7. A snubbing jack for effecting, against confined well pressure, the longitudinal movement of a string of pipe having collars of larger diameter than the pipe, comprising: a cylinder adapted to surround said pipe and collars substantially coaxially, means, including a piston movable longitudinally in the cylinder, adapted to engage one of said collars, and means for passing fluid under pressure into the cylinder for compelling said movement in either direction.

8. In well equipment, apparatus for controlling the longitudinal movement of a string of pipe in a well having confined fluid pressure, said pipe having collars of larger diameter than the pipe, comprising: means forming a fluid tight continuous, cylindrical column having sealing means at its lower end to seal against said pipe string and adapted to pass said pipe and said collars, oppositely directed slips in the column adapted to engage the pipe for optionally preventing said movement in either direction, and means, including a piston, in said column adapted to engage and move said pipe string in either direction.

9. Equipment adapted to control the insertion and withdrawal of a pipe in a well having confined fluid pressure, comprising: a cylindrical column adapted to surround said pipe substantially coaxially, said column being closed at its upper end against emergence of the pipe, and having sealing means at its lower end adapted to effect fluid tight closure on the pipe, whereby said column is adapted to form a continuous fluid tight chamber, oppositely disposed slips in said chamber adapted to engage the pipe for preventing its movement, and pipe engaging means and a piston movable longitudinally in said chamber for effecting said insertion or withdrawal.

10. In well derrick equipment, means for controlling the longitudinal movement of a pipe in either direction comprising in combination: a rotary drilling machine having a sealing member for effecting closure on said pipe, a substantially continuous, fluid tight, cylindrical column adapted to surround the pipe coaxially and to be suspended from the derrick and anchored to said machine, and a plurality of means in said column adapted to engage the pipe for optionally preventing or compelling said movement.

11. In equipment for controlling the insertion and withdrawal of pipe in a well having confined fluid pressure, a cylindrical column comprising a blowout preventer adapted to effect fluid tight

closure on said pipe, a sliphead secured to the preventer and having means adapted to optionally engage and hold the pipe against longitudinal movement in either direction, a cylinder secured to the sliphead, said preventer, said sliphead and said cylinder forming a continuous fluid

tight chamber adapted to surround the pipe substantially coaxially, and means, including a piston, in the cylinder adapted to engage the pipe and to effect said insertion or withdrawal with or without the aid of well pressure.
